UNITED STATES PATENT OFFICE.

JAMES M. CHAFFIN, OF BRECKENRIDGE, MISSOURI.

SHINGLING-HATCHET AND GAGE.

1,174,120.

Specification of Letters Patent. Patented Mar. 7, 1916.

Application filed November 29, 1915. Serial No. 64,143.

To all whom it may concern:

Be it known that I, JAMES M. CHAFFIN, a citizen of the United States, residing at Breckenridge, in the county of Caldwell 5 and State of Missouri, have invented certain new and useful Improvements in Shingling-Hatchets and Gages, of which the following is a specification.

This invention relates to an improved 10 shingling hatchet and the principal object of the invention is to provide the hatchet with an improved type of gage which is so constructed and mounted that the hatchet may be used for ascertaining the proper 15 position for the next row of shingles.

Another object of the invention is to provide the hatchet blade with an improved type of side grooves having their upper ends communicating with the edge of the hatchet 20 and to provide the gage block with an improved construction so that the gage block can be slidably connected with the hatchet blade by means of fingers extending into the side grooves thereof, the fingers being positioned 25 for permitting easy removal of the gage block from the hatchet blade.

Another object of the invention is to so construct the side grooves and gage block 30 that the lugs carried by the block and fitting into the grooves of the blade may be formed integral with the block.

This invention is illustrated in the accompanying drawings, wherein:—

Figure 1 is a view in side elevation showing a shingling hatchet provided with the improved gage. Fig. 2 is a view in end elevation of the shingling hatchet shown in Fig. 1. Fig. 3 is a view in elevation of the gage shown in Figs. 1 and 2. Fig. 4 is a 40 top plan view of the gage with the spring shown in section. Fig. 5 is a bottom plan view of the gage.

The shingling hatchet indicated in general by the numeral 10 is provided with a 45 blade 11 and driving head 12, the end of the driving head being roughened if desired. The blade 11 is provided along one edge with notches 13 and is further provided with a scale 14 designating the distance 50 in inches or fractions thereof from the end of the driving head 12 to the various notches. Each side of the blade is provided with a longitudinally extending groove 15 which has its upper end portion 55 provided with the necks 16 leading to the notched edge of the blade. It will thus be

seen that the construction of the shingling hatchet is similar to the construction of hatchets now in use with the exception of the provision of notches 13, grooves 15 and 60 the scale markings 14.

The gage includes a body portion or block 17 which is slidably mounted upon the blade and is provided with lugs 18 fitting 65 into the grooves 15. These lugs are positioned as shown in Fig. 3 and of course are spaced apart the proper distance so that when putting the block or body portion in place the lugs 18 can pass through the necks 16, and then move downwardly into the 70 grooves 15. After the block is in place as shown in Figs. 1 and 2, these lugs will prevent the block from moving transversely of the hatchet blade but will permit the block to move longitudinally thereof for adjustment. The leaf spring 19 which forms a 75 latch for the block or slide 17 has one end portion fitting into the block and held in place by means of set screws 20 passing through openings 21 in the outer wall of the 80 block. This latch is provided at its free end with a tooth 22 fitting into the notches 13 and releasably holding the block or slide in an adjusted position upon the blade. It is 85 of course understood that this latch 19 will be of sufficient length so that when the tooth fits into one of the notches 13, for instance the one marked 4, the shingle engaging flange 23 will be four inches from the end 90 of head 12.

When in use the first row of shingles will be nailed upon the roof and the gage will then be set to the proper distance from the end of the driving head 12. For instance, if it is desired to have four inches of the shingle exposed, the gage will be set as 95 shown in Figs. 1 and 2 and the hatchet can then be placed flat upon the shingle nailed to the roof with the flange 23 engaging the edge of the shingle. The shingle to be 100 nailed upon the one already in place will then be put upon the roof with its edge fitting against the driving head. The securing nail for the second shingle will of course have already been driven into the same and this second shingle can then be held in place and the nail then driven into place with the hatchet. It will thus be seen that there has 105 been provided a gage which can be connected with the blade of the shingling hatchet and can be easily moved to the proper position. 110

If it is desired to use this hatchet for cutting in the usual manner and it is not desired to risk having the gage broken, this gage can be easily removed and put away until again needed. It will also be seen that if it is desired to replace or straighten the latch 19, the block or slide can be disconnected from the blade of the hatchet and the new spring put in place or the necessary 10 repairs made to the spring already in use.

What is claimed is:—

1. A shingling hatchet provided with a blade and a driving head, said blade being provided with notches leading from one edge 15 and with grooves in its side faces extending parallel to the notched edge and having their upper ends provided with necks communicating with the notched edge, a block slidably mounted upon said blade and provided 20 with lugs fitting into the grooves thereof, said lugs being positioned to pass through said necks, a leaf spring connected with said block and constituting a latch having its free end portion provided with a 25 tooth for fitting into the notches of said blade to releasably hold said block in an adjusted position upon the blade, and a flange extending from said block and constituting an abutment.
- 30 2. A shingling hatchet provided with a driving head and a blade, said blade being provided with notches leading from one edge and with longitudinally extending grooves in its side faces terminating at their upper 35 ends in necks leading to the notched edge of

said blade, an abutment block slidably mounted upon said blade and provided with lugs fitting into the grooves thereof, and a latch carried by said block and fitting into the notches of said blade to releasably hold the block in an adjusted position upon the blade.

3. A shingling hatchet including a head and a blade, the blade being provided with longitudinally extending grooves terminating at their upper ends in necks leading to the edge of the blade, a block slidably mounted upon said blade and provided with lugs fitting in said grooves and positioned to pass through said necks, a flange extending 50 from said block, and means for releasably holding said block in an adjusted position upon said blade.

4. A shingling hatchet provided with a driving head and blade, the blade being provided with longitudinally extending grooves terminating in necks leading to the edge thereof, a gage element slidably mounted upon said blade and provided with extensions fitting into said grooves and positioned to pass through said necks, and means for releasably holding said gage element in an adjusted position upon said blade.

In testimony whereof I affix my signature in presence of two witnesses.

JAMES M. CHAFFIN.
